UNITED STATES PATENT OFFICE.

CHARLES R. ALLEN, OF OAKLAND, CALIFORNIA.

DESIGN FOR A BRIQUET.

No. 38,206.

Specification for Design.

Patented Aug. 28, 1906.

Application filed May 18, 1906. Serial No. 317,643. Term of patent 14 years.

To all whom it may concern:

Be it known that I, CHARLES R. ALLEN, a citizen of the United States, residing at Oakland, in the county of Alameda and State of California, have invented a new, original, and ornamental Design for Briquets, of which the following is a specification, reference being had to the accompanying drawings, forming part thereof.

Figure 1 is a perspective view of a briquet,

showing my new design. Fig. 2 is a plan view of a briquet, showing my new design.

I claim—

The ornamental design for a briquet, as shown.

CHARLES R. ALLEN.
